DESIGN FOR A COMBINED TIE CLIP AND PENCIL

Lawrence E. Baer, Attleboro, Mass., assignor to
Swank Products, Inc., a corporation of Delaware

Application September 18, 1940, Serial No. 95,179

Term of patent 14 years

To all whom it may concern:

Be it known that I, Lawrence E. Baer, a citizen of the United States of America, residing at Attleboro, county of Bristol, State of Massachusetts, have invented a new, original, and ornamental Design for a Combined Tie Clip and Pencil, of which the following is a specification, reference being had to the accompanying drawing forming a part thereof.

Fig. 1 is a top plan view of a combined tie clip and pencil showing my new design;

Fig. 2 is a side elevation;

Fig. 3 is a perspective view thereof; and
Fig. 4 is a bottom plan view of the disclosure of Figure 1.

My design is characterized by the specific configuration of the clip member in combination with a mechanical pencil of the configuration as shown.

I claim:

The ornamental design for a combined tie clip and pencil, substantially as shown and described.

LAWRENCE E. BAER.
